(57) **CLAIM**

The ornamental design for a knitting loom set as shown and described.

DESCRIPTION

FIG. 1 is a perspective view of a first component of a knitting loom set, shown separately for ease of illustration; FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a second component of the knitting loom set, shown separately for ease of illustration; FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a perspective view of a third component of the knitting loom set, shown separately for ease of illustration; FIG. 18 is another perspective view thereof;

FIG. 19 is a front elevational view thereof;

FIG. 20 is a rear elevational view thereof;

FIG. 21 is a left side elevational view thereof;

FIG. 22 is a right side elevational view thereof;

FIG. 23 is a top plan view thereof;

FIG. 24 is a bottom plan view thereof;

FIG. 25 is a perspective view of a fourth component of the knitting loom set, shown separately for ease of illustration; FIG. 26 is another perspective view thereof;

FIG. 27 is a front elevational view thereof;

FIG. 28 is a rear elevational view thereof;

FIG. 29 is a left side elevational view thereof;

FIG. 30 is a right side elevational view thereof;

FIG. 31 is a top plan view thereof;

FIG. 32 is a bottom plan view thereof; and,

FIG. 33 is a perspective view of the knitting loom set.

The knitting loom set are shown with a symbolic break in its length and the appearance of any portion of the knitting loom set between the break lines form no part of the claimed

(Continued)

design. The other broken lines in the drawings depict portions of knitting loom set and form no part of the claimed design.
